UNITED STATES PATENT OFFICE

121,524

DESIGN FOR A PIPE

Henry T. Schiff, Chicago, Ill.

Application May 13, 1940, Serial No. 92,326

Term of patent 3½ years

To all whom it may concern:

Be it known that I, Henry T. Schiff, a citizen of the United States of America, residing at Chicago, Illinois, have invented a new, original, and ornamental Design for a Pipe, of which the following is a specification, reference being had to the accompanying drawing, forming a part thereof.

Fig. 1 is a side elevational view; Fig. 2 is a

top plan view, and Fig. 3 is an end elevational view, showing a pipe embodying my new design.

The dominant feature of my design resides in the curved metal stem with its curved ribs and grooves.

I claim:

The ornamental design for a pipe, substantially as shown and described.

HENRY T. SCHIFF.
